Specification of Letters Patent.

Patented Oct. 28, 1913.

Application filed November 28, 1910. Serial No. 594,423.

To all whom it may concern:

Be it known that we, RAYMOND C. MITCHELL and HARRY M. NEER, citizens of the United States, residing at Springfield, 5 in the county of Clark and State of Ohio, have invented certain new and useful Improvements in Explosive-Engines, of which the following is a specification, reference being had therein to the accompanying 10 drawings.

This invention relates to explosive engines and more particularly to valve operating mechanism for such engines.

The object of the invention is to provide a 15 valve-operating mechanism which will positively move both the inlet valve and exhaust valve toward and from their seats; which will be so arranged as to enable a short, light cushioning spring to be employed on 20 the valve stem; which will be very simple in its construction and will embody a minimum number of parts.

It is also an object to provide a valve cage adaptable either for the inlet or exhaust 25 valve and of such a construction that it is readily accessible, can be easily removed from the engine and repaired, and which will be inexpensive to manufacture.

A further object of the invention is to 30 provide an oil pump which will be directly connected with the engine shaft and will distribute the oil to the several bearings.

In the accompanying drawings, Figure 1 is a top, plan view of an explosive engine 35 embodying our invention; Fig. 2 is a transverse, sectional view, taken on the line $\alpha-\alpha$ of Fig. 1 and looking in the direction of the arrows; Fig. 3 is a detail view of one of the valve-operating levers.

In these drawings, we have illustrated one 40 embodiment of our invention and have shown the same as applied to a four cylinder automobile engine, the main features of construction of which are well known. The 45 several cylinders, which are indicated at 1, are cast in pairs and each cylinder is provided with a piston 2 connected by a piston rod 3 with a crank shaft 4 extending longitudinally to the engine and arranged beneath 50 the cylinders. This crank shaft and its co-operating parts are inclosed in a suitable crank casing 5, the lower portion of which is preferably depressed, as indicated at 6, to form an oil receptacle. The bottom 55 of this receptacle is preferably inclined to

form a well at one end thereof with which a suitable oil pump communicates. This oil pump comprises a vertically arranged cylinder 7, the lower end of which communicates with the oil receptacle 6 and in which is mounted a suitable piston 8, the upper end of which is provided with a connecting member or rod 9 having a bearing strap 10 which extends about an eccentric 11 carried by the crank shaft 4, thereby directly connecting the piston 8 to the crank shaft and causing the pump to be actuated directly from the shaft. The operation of the pump forces the oil through a pipe 12 to a distributor 13 through which it is distributed, by 60 pipes 14, to the several bearings of the crank shaft.

The engine is designed particularly for use with automobiles, and, when so used, it is preferable that a shield 15 should separate the oil receptacle 6 from the body of the crank casing 5 to prevent the body of oil in this receptacle entering the crank casing. This shield is provided with openings 16 to permit the oil to return to the oil receptacle. A suitable gage 17 communicates with the receptacle and indicates the amount of oil contained therein.

The construction of the several cylinders and the valve operating mechanism therefor is substantially the same and we will, therefore, describe a single cylinder and its valve-operating mechanism and it will be understood that this description applies to the four cylinders of the engine. Each cylinder is provided at its upper end with an inlet chamber 18 and an exhaust chamber 19 communicating respectively with a supply pipe 20 and an exhaust pipe 21. The inlet chamber and the exhaust chamber are substantially similar in their construction and their valve mechanisms are substantially the same. These chambers are preferably arranged on the opposite sides of the vertical center of the cylinder and have their upper ends diverging in a plane extending transversely to the engine shaft. Mounted in each valve chamber is a valve cage comprising a ring 22 arranged to fit snugly against the wall of the lower part of the chamber and having its lower edge shaped to form a valve seat, as indicated at 23. This ring is connected by means of arms 24 with a hollow shank 25. To the opposite end of this hollow shank is secured a disk 110

26 which is screw-threaded into the upper end of the chamber wall, thus rendering the cage as a whole readily removable. The valve comprises a disk-like valve member 27 which seats against the lower edge of the ring 22 and has a stem 28 extending through the hollow shank 25 of the cage and to a point beyond the outer end of the cage and is thus readily removable with the cage.

10 Suitable means are provided for positively seating and unseating the inlet and exhaust valves at the proper time during the operation of the engine, and, for the sake of simplicity of construction, it is preferable that the same actuating device should operate the two valves of each cylinder. In the present instance we have provided a cam shaft 29 extending longitudinally to the engine between the diverging portions 20 of the cylinders, in which these valve chambers are formed. The cam shaft is connected with the crank shaft by means of a miter gear 30 secured to the cam shaft and meshing with a similar gear 31 on a vertical shaft 32, the lower end of which is connected by similar gears with the crank shaft. Preferably, the ratio of these gears is two to one so that the cam shaft will make but one revolution for each two revolutions of 30 the crank shaft. The valve-actuating devices comprise cams 33 rigidly secured to the cam shaft 29 and operatively connected with the respective valves by means of suitable connecting members. In the present 35 instance there are four cams, one for each cylinder, and each cam operates both the inlet valve and the exhaust valve of its cylinder. The connecting members, by means of which the cams are connected with the 40 valves, comprise bell crank levers 34 which are pivotally mounted on the engine frame at 35. One arm of each lever is arranged substantially vertically and is provided with a pin 35 which enters a groove 37 in the periphery of its cam. The other arm of the bell crank lever extends at an angle to the arm having the pin and is connected to the valve stem, this connection being preferably formed by bifurcating the end of the 45 lever arm, as indicated at 38, and passing the same about the valve stem 28. The upper end of this valve stem is reduced to form a shoulder 39 against which the lower edges of the bifurcated portion of the lever arm 50 rest. A spring 40 is coiled about the reduced portion of the stem above the lever arm and is confined between the latter and a collar 41 mounted on the upper end of the stem. The connecting levers for the inlet and 55 exhaust valve are, of course, arranged on opposite sides of the cam shaft and the cam will actuate these levers at different times during the operation of the engine, the time being controlled by the character of the 60 groove in the cam and the points at which

the levers are connected with the cam. Consequently, the operation of the cam shaft will first cause the inlet valve to positively be moved into its open position at the beginning of the suction stroke of the piston, and, after a sufficient charge of gas has been delivered to the cylinder, to be positively moved to its closed position. After the explosion and at the beginning of the exhaust stroke of the piston the exhaust valve is positively moved to its open position and at the end of this stroke is positively seated. Further, by operating the valves in this manner we are enabled to employ a very short, light spring which is arranged on the outer sides of the valve arm or lever to act as a cushion and to retain the valve firmly against its seat.

70 A bracket 42 is rigidly secured to one end of the engine, preferably above the fly wheel and forms a support for the magneto which is indicated at 43. The magneto is preferably operated from the cam shaft and is connected thereto by gears 44 and 45. By 75 mounting the magneto in this manner it is supported above the base of the engine and in a position where it will not be affected by any accumulations of dust or oil which may form about the base of the engine.

80 The operation of the device will be clearly understood from the foregoing description of the several parts thereof and it will be apparent that we have provided a valve-actuating mechanism in which each valve actuating device positively controls both the inlet valve and the exhaust valve for 85 its respective cylinder, and in this manner the number of valve-actuating devices necessary to control the valves of the engine is reduced by half from what is necessary 90 where each valve is controlled by a separate device. Further, these actuating devices and their connecting members are of a very simple character, will not be easily disarranged or 95 broken and are readily accessible for adjustment or repair should this be necessary; also the valves themselves are mounted in 100 valve cages of a simple, inexpensive construction which, together with the valve, can be readily removed from the valve 105 chambers. Further, the magneto is supported in a position where it will be free 110 from dust and dirt and the oil pump is directly connected with the engine shaft, thereby 115 eliminating the usual connecting mechanism.

120 While we have shown and described one embodiment of our invention it will be understood that this form of the mechanism is chosen only for the purpose of illustration and that the several parts thereof are capable of being constructed and arranged in different manners, and it will, therefore, be understood that we do not desire to be limited to the details of construction shown 125 130

and described, for obvious modifications will occur to a person skilled in the art.

Having thus fully described our invention, what we claim as new and desire to secure by Letters Patent, is:

An engine comprising a plurality of cylinders, a shaft arranged near the upper ends of said cylinders and extending longitudinally of said engine, each cylinder having an inlet port on one side of said shaft and an outlet port on the other side thereof, valves to control the respective ports, a cam mounted on said shaft adjacent to each cylinder, and a pair of bell crank levers dis-

posed on opposite sides of the shaft and fulcrumed on the respective cylinders, said levers being arranged to rock in a plane parallel to said shaft, one arm of each lever having operative engagement with the cam and the other arm of each lever being respectively connected to one of the valves.

In testimony whereof, we affix our signatures in presence of two witnesses.
